UNITED STATES PATENT OFFICE

WALTER A. MAYES, OF YORK, PENNSYLVANIA, ASSIGNOR TO MARTIN-PARRY CORPORATION, OF YORK, PENNSYLVANIA, A CORPORATION OF PENNSYLVANIA

SEALING STRIP FOR BOTTOMS OF VEHICLE BODIES

Application filed July 18, 1927. Serial No. 206,620.

This invention relates to improvements in vehicle bodies of the commercial type.

The object of the invention is to provide a sealing strap, or what is termed in the trade 5 as a "floor strip," to be used in connection with the bottom boards of commercial vehicle bodies to seal the spaces therebetween and at the same time to permit the boards to have sufficient freedom to "weave" without dis- 10 turbing the operation of the sealing strip.

More specifically, the invention comprises a sealing strip or floor strap which is made of sheet metal and which comprises a vertical extension adapted to be secured to one edge 15 and a horizontal extending portion extending over the space between the floor boards and having as a continuation thereof a rebent longitudinal corrugated portion extending beyond the vertical attaching portion and pro- 20 vided with a down-turned lip for engaging the floor board.

Numerous other inherent advantages of the invention will be apparent to those skilled in the art from a reading of the following speci- 25 fication in which

Fig. 1 represents a top plan view of the bottom of a commercial vehicle body showing the floor boards with the sealing devices attached thereto;

Fig. 2 is a sectional view of a pair only of the floor boards and having the interposed sealing strip associated therewith, and

Fig. 3 is a detailed view of the strip before it has been attached to the floor board.

Fig. 4 is a cross sectional view of the strip.

Referring now more particularly to the drawings, wherein like reference characters represent corresponding parts, the numeral 1 designates a commercial vehicle body which 40 may be of any well known type. This body is provided with longitudinally extending floor boards 2. In this type of body, the floor boards are spaced from one another and the invention comprises a sealing device or floor

45 strap to prevent the escape of materials from for confines of the body and the ingress of foreign materials therein. To this end, I provide a vertical extension 3 having a horizontal portion 4 and a returned bent portion 5. The

50 returned portion is provided with a series of

longitudinally extending corrugations 7 and a downwardly extending lip 8 engaging one of the floor boards. Normally the vertical attaching portion 3 extends at an acute angle with respect to the horizontal sealing portion 4 as shown in Fig. 4. However, when the device is applied to the body this angular formation causes the horizontal extension to very tightly engage the adjacent floor board where it is yieldably held in position.

The returned bent corrugated portion 7 ex- 55 tends in a horizontal direction and the convex parts 8 of the corrugations abuttingly engage the upper ends of the horizontal sealing portion 4 at each side of the space existing be- 60 tween the floor boards as fully shown in Fig. 2. The floor strap or sealing strip above de- 65 scribed may be employed with the bottoms of commercial bodies without any modification of the floor boards and is capable of permit- 70 ting weaving and expansion or contraction of the boards within certain set limits. The at- 75 tachment may be also applied to bottoms hav- 80 ing variant degrees of spaces between the floor boards. It will be observed that the horizon- 85 tal extension 4 completely covers the space be- 90 tween the floor boards and is maintained yieldably or tightly in engagement with the adjacent floor board due to the fact that the vertical extension 3 is normally at an acute angle before its application to the floor board after which it is forced into a right angle position, thus firmly urging the horizontal ex- 95 tension downwardly. The returned bent horizont- 100 ally extending portion 5 spans the crevice between the floor boards and overlies the vertical extension, and the convex por- tions of the corrugations of the returned bent extension tightly engage the portion 4 and tend to firmly maintain it in position but per- mitting the necessary expansion and contrac- tion of the floor boards and the weaving there- of without breaking the sealing effect of the attachment.

Having thus described the invention, what I claim is:

In a vehicle body, the combination with a bottom composed of a series of spaced apart floor boards, a sealing device having a vertical portion engaging the edge of one of said floor

boards, a horizontal extension spanning the space between such floor boards and resiliently engaging the upper surface of the adjacent board, a returned bent portion overlying the horizontal and vertical portions aforesaid, said returned bent portion having corrugations formed therein and the convex portions of which engage the horizontal extension at points on each side of the space between said floor boards.

⁵ 10 In testimony whereof I affix my signature.
WALTER A. MAYES.
